UNITED STATES PATENT OFFICE

JOHAN VICTOR SVENSON, OF AUGUSTENDAL, STOCKHOLM, SWEDEN

BURNER FOR LIQUID FUEL

Application filed October 17, 1927, Serial No. 226,753, and in Sweden November 20, 1925.

The present invention relates to an improvement in such burners for liquid fuel in which below the nozzle, through which the evaporated fuel escapes, is provided a vaporizing chamber wherein is placed a heat storing vaporizing member provided with passages. This vaporizing member has hitherto been only loosely inserted in the vaporizing chamber, causing the disadvantage that 5 said member, especially when the burner has been in use for some time, will be out of necessary metallic contact with the walls of the chamber, even if it, when inserted, was in such a contact with said walls, resulting 10 in an inadequate transmission of heat from the walls of the chamber to said member. A loose insertion of said member in the vaporizing chamber involves, however, also other disadvantages. It is evident that the fuel 15 when being forced up in the vaporizing chamber ought to be evenly and continuously evaporated in accordance with its entrance into that part of the chamber where vaporization temperature is prevailing, but in a chamber 20 where the vaporizing member is inadequately heated and besides loosely inserted and even has an opportunity to change position or is somewhat movable in the chamber, the vaporization will in a great degree be uneven 25 and thus create a pulsating stream of vaporized fuel according as a quantity of fuel now and then is suddenly evaporated. The consequence hereof is that the flame will be uneven and if the vaporizing member then has 30 an opportunity to displace itself in the chamber the effect of such a displacement may be that every time it takes place a clearly audible blow is noticed. The effect of such blows may be that small coke-like particles may be 35 detached from the vaporizing member or the wall of the vaporizing chamber and if such a particle strongly heated is falling down in the fuel container below at an instant when only a small quantity of fuel is left in the 40 container, an explosion may take place, as the main part of the container then is filled with air mixed with vaporized fuel.

This invention has for its object to eliminate said disadvantages and is chiefly 45 characterized thereby that the vaporizing

member at its lower end is effectively acted upon by a member the effect of which is to force the vaporizing member upwards in good contact with the walls and upper end of the vaporizing chamber.

One form of construction of a burner provided with a vaporizing chamber and a vaporizing member of the kind in question and with an arrangement according to this invention are illustrated as an example on the accompanying drawing in a vertical section.

Below the nozzle 1, through which the evaporated fuel escapes, is the vaporizing chamber 2 wherein the vaporizing member 3 is placed. This latter has the same cross sectional shape as the vaporizing chamber and is of such a size, that it all round along its entire length and preferably also at the upper end will be in good contact with the walls of the chamber. The chamber 2 may be of the same cross section all over but preferably it is tapering somewhat upwards in order that the member 3 which is of the same shape, may better and more firmly, all over, come in good contact with the walls of the chamber when being pressed upwards. The member 3 is suitably pressed upwards by means of a threaded ring 4 screwed so far into the lower part of the chamber that the member will be well pressed into its place in the chamber. It is evident from the foregoing that the fuel rising through the tube 7 has free access to the member 3. This may suitably be manufactured of wire-gauze but it may also constitute a solid body of some suitable metal, in which case the same must be provided with suitable passages in which the fuel that passes through the same may be vaporized.

It is obvious that the above indicated disadvantages are eliminated in a burner the vaporizing member of which is kept in its place by an arrangement according to this invention.

Having now described my invention what I claim as new and desire to secure by Letters Patent is:

1. A burner for liquid fuel, including a nozzle for the passage of vaporized fuel, a nozzle supporting member having a vaporizing chamber located below the nozzle, a heat

storing vaporizing member located within said chamber and provided with passages, and a member movably mounted in the supporting member adapted to exert pressure upon the vaporizing member to maintain the latter in close contact with the supporting member.

2. A burner for liquid fuel, including a nozzle for the passage of vaporized fuel, a nozzle supporting member having a vaporizing chamber located below the nozzle, a heat storing vaporizing member located within said chamber and provided with passages, and a member movably mounted in the supporting member adapted to exert pressure upon the vaporizing member to maintain the latter in close contact with the supporting member, said last mentioned member being of annular form and being located wholly within the supporting member.

3. A burner for liquid fuel, including a nozzle for the passage of vaporized fuel, a nozzle supporting member having a vaporizing chamber located below the nozzle, a heat storing vaporizing member located within said chamber and provided with passages, and a member movably mounted in the supporting member adapted to exert pressure upon the vaporizing member to maintain the latter in close contact with the supporting member, said vaporizing chamber and the storing member being of tapered form whereby to produce a wedging effect on the latter member.

35 4. A burner for liquid fuel, including a nozzle for the passage of vaporized fuel, a nozzle supporting member having a vaporizing chamber located below the nozzle, a heat storing vaporizing member located within said chamber and provided with passages, and a member movably mounted in the supporting member adapted to exert pressure upon the vaporizing member to maintain the latter in close contact with the supporting member, said last mentioned member being annular and externally threaded and located wholly within the supporting member.

In witness whereof I have hereunto set my hand.

50 JOHAN VICTOR SVENSON.
